UNITED STATES PATENT OFFICE.

HARRIS ALEXANDER, OF SAN ANTONIO, TEXAS.

DESIGN FOR A TIRE.

Application filed August 31, 1921. Serial No. 497,396. Term of patent 14 years.

To all whom it may concern:

Be it known that I, HARRIS ALEXANDER, of a tire showing my new design. a citizen of the United States of America, residing at San Antonio, in the county of Bexar and State of Texas, have invented a new, original, and ornamental Design for a Tire, of which the following is a specification, reference being had to the accompanying drawing, forming part thereof.

The drawing is a plan view of a portion

I claim:

The ornamental design for a tire, as shown.

HARRIS ALEXANDER. [L.S.]
